REFRIGERANT PLATES

Herman W. Kleist, Hollywood, Ill., assignor to Dole
Refrigerating Company, Chicago, Ill., a corporation
of Illinois

Application January 9, 1957, Serial No. 633,299

5 Claims. (Cl. 62—439)

My invention relates to an improvement in heat exchange plates, and has for one purpose to provide a plate of the type used in refrigeration, which is efficient in use, strong in structure, and simple to manufacture.

Another purpose is to provide a heat exchange plate which includes a pressed or rolled metal coil or evaporator passage structure formed of sheet metal.

Another purpose is to provide a heat storage plate, of the type used, for example, in truck refrigeration, in which a rolled or stamped coil component is combined with a welded, assembled plate structure adapted to hold an eutectic in heat exchange relation with the coil.

Another purpose is to provide such a plate in which various parts of the plate are held or urged together by a pressure differential between the interior and the exterior of the plate.

Other purposes will appear from time to time in the course of the specification and claims.

I illustrate my invention more or less diagrammatically in the accompanying drawings, wherein:

Figure 1 is a plan view;

Figure 2 is a side view of the structure of Figure 1;

Figure 3 is a view of the interior of the plate with the top removed;

Figure 4 is a plan view of a spacer employed;

Figure 5 is a perspective of another spacer;

Figure 6 is a section on the line 6—6 of Figure 2, on an enlarged scale;

Figure 7 is a section on the line 7—7 of Figure 1, on an enlarged scale; and

Figure 8 is a detail.

Like parts are indicated by like symbols throughout the specification and drawings.

Referring to the drawings, and, for example, to Figure 6, A refers generally to a preferably rolled sheet metal coil structure, and B refers to the rest of the plate. With reference now to the general showing of Figures 1, 2, 6 and 7, the coil assembly is formed of two sheet metal layers, indicated, for example, at 1 and 2 in Figures 6 and 7. Whereas, in these figures a separation is indicated between the layers 1 and 2, it will be understood that in the manufacture of the rolled coil the metal may be so closely bonded together, where the two sheets abut, as to evidence no visually observable separation between the two layers. It is thought best, however, to illustrate the two layers in the drawings as shown, that the method of making the plate may be the clearer.

Before further describing the coil, it will be well to point out that the coil assembly A serves as one side of a plate interior in which a suitable eutectic may be contained. The plate is formed, for example, of a plane-surfaced side wall 3 having circumferentially extending edge flange or flanges 4 which terminate at their upper outer edges in outwardly extending flange portions 5. These flange portions 5 abut, and may be welded or otherwise secured to the marginal portion of the rolled coil assembly A. It will be understood, of course, that

the parts in the position shown, for example, in Figures 5 and 6, are assembled to form a water-tight and gas-tight container. Within the container or housing so formed I provide the spacing structure wall shown, for example, in Figures 3, 6 and 7. I employ, for example, a plurality of channels, generally indicated as 6, which have parallel flanges 6a, 6b connected by a cross-piece 6c. The cross-piece 6c, as shown in Figures 3 and 8, are penetrated by apertures 6d. The flanges 6a and 6b are penetrated by apertures or gaps 6e, the purpose of which will later appear. It will be understood that the channel members 6 are arranged with their free edges of the flanges 6a and 6b abutting the inner surface of the plate side wall 3, while the connecting portions or webs 6c abut the later described coil of the coil assembly A. As will be clear from Figure 3, the channels 6 are of varying length, since some free inside space within the plate is desired.

I find it advantageous to employ two types of spacers or positioning members to make sure that the spacing channels 6 are themselves arranged in desired relationship within the plate. A basic type of spacer or bracket is shown, for example, in Figure 5, and is shown in position at various points in Figure 3. These brackets 7 have end flanges 7a connected by perpendicular portions 7b with the intermediate body portion 7c. The spacer flanges 7a either abut one of the circumferential edge wall portions 4 or else abut the special spacer body illustrated as 8 in Figure 4. This spacer 8 has at one end a flange 8a abutting one edge wall 4 and at the opposite end, and at right angles to the flanges 8a, a flange 8b which abuts another of the edge wall portions 4. The spacer or bracket 8 is shown in position at the lower right-hand corner of Figure 3, and receives the ends of the shorter of the spacing fins or channels 6, and thus serves to keep an open space, indicated as C, within the plate. The individual channels are spaced apart by use of the brackets 7, as illustrated in Figure 5 and as shown in position in Figure 3. By the spacers and brackets above described the spacing channels 6 are uniformly or substantially arranged within the plate in their desired relationship to the plate side wall 3 and the coil assembly A. The free space C leaves room for the later described fittings. Since the height of the brackets or spacers 7 and 8 is less than the height of the interior of the plate there is no damaging interference with the movement of eutectic within the plate. It will be understood that the spacers may be fixed in position in any desired manner, or may be merely inserted loose, since they cannot escape from their assembled position. The aperture 6d permits the relatively free flow of eutectic throughout the interior of the plate.

Considering, next, the coil assembly A, it will be understood that in the formation of the coil the two sheet metal plates or layers 1 and 2 are fed between appropriately formed rollers by an already known procedure, not of itself part of the present invention, to produce the final coil. In practice, the two sheets of metal are trimmed to proper size and dimensions and are rolled to bond the two sheets together except along the contours of the desired coil. The result is a composite sheet in which the layers 1 and 2 are bonded together throughout a substantial part of their area, but are separated in such fashion as to define a coil pattern. Along this coil pattern the two sheets are rather widely separated, as shown at 1a and 2a in Figure 6. In the present plate the pattern includes a length 9 along one side of the plate which connects to a length 10 along one edge of the plate and a length 11 along the opposite long side of the plate. Beyond the length 11 is a series of straight stretches 12, the length 11 and the successive lengths 12 being con-

neected together by arcuate bends or connecting portions 13. The last straight stretch 12 terminates with a 90° curve 14 which, in turn, extends by a straight section 15 which is at right angles to the length 11 and 12. The initial stretch 9 is connected by a 90° bend 16 to the edge of the plate. The above coil structure may, for example, be made of two sheets of aluminum. In that event, I find it advantageous to weld copper tubing fittings as shown at 17 and 18. To these fittings any suitable outside connecting ducts or pipes 19 and 20 may be secured.

Assume that the coil elements A, formed as above described, and properly trued and flat, has been seam-welded or otherwise secured to the flanges 5 of the edge walls 4. The parts are so proportioned that the inwardly projecting coil portion 2a abuts the webs 6c of the spacing channels 6. The space about the channels and between the side wall 3 and the coil assembly A may be substantially filled by a suitable eutectic. This eutectic may, for example, be filled through any suitable filling plug or fitting, more or less diagrammatically indicated at 21 in Figures 1 and 2. Assume that the interior of the plate has been substantially filled or adequately filled with a suitable eutectic, it is important to maintain a proper heat exchange relation between the coil and the spacing channels 6, and to prevent any tendency of the plate to take a damaging bulge, due to successive freezing and thawing of the eutectic within the plate. I find it highly advantageous to withdraw air from the interior of the plate and thus to maintain a less-than-atmospheric pressure within the plate. As a result of this less-than-atmospheric pressure the outside atmospheric pressure firmly urges the coil assembly A and the plate side wall 3 together about the spacing channels 6. Thus the edges of the flanges 6a and 6b abut the inner surface of the plate side wall 3, and the webs 6c firmly abut the inwardly projecting coil portion 2a. I find it advantageous to withdraw the air from within the plate through a suitable fitting illustrated at 22 in Figures 1 and 2. This fitting may include a check valve in the form of a ball 23, and may further have an outside screw closure or plug 24. After the plate has been adequately filled with the eutectic it is preferably placed on edge, and a suitable proportion of the air within the plate is withdrawn. Thereafter, the outside plug 24 may be put in position, and there will be no escape of air into the interior of the plate. The pressure differential between the interior of the plate and the ambient air outside may be widely varied within reasonable limits. An internal negative pressure of two or three inches of vacuum may be adequate in some circumstances. In other circumstances, ten or fifteen inches of vacuum, or more, may be drawn. With thin aluminum sheets, however, it is undesirable to employ too high vacuum, since some rippling of the sheets, between edges or points of support, may take place.

It will be understood that my plate may be used in a variety of heat transfer situations, including both refrigeration and heating. However, I find it particularly adaptable for service as a plate used in refrigeration. Under such circumstances I find it important to have at least one surface of the plate completely plane for ease in defrosting. Both forms of the plate herein shown provide a plane plate side face and also an opposite face which, since it is broken only by an outwardly offset half of a coil, is also readily defrosted by brushing or scraping. Both forms of the plate lend themselves to manufacture by stamping or rolling sheet metal. It will be observed that both plates include only three wall parts, which are easily stamped or rolled.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic rather than as limiting me to my precise showing herein.

The use and operation of the invention are as follows: I provide a plate, the coil element of which can advantageously be made by roll bonding. This is particularly the case where aluminum sheet is employed. The coil thus formed may be light in gauge and relatively flexible. I find it important to provide adequate supporting and spacing means for the coil, in applying it as a component to an eutectic or hold-over plate. In practice, it is important that no spacing means be directly secured or welded to the coil component. I find it advantageous to maintain a spacing structure within the plate, in the form, for example, of a plurality of spacing channels above described. This spacing structure is proportioned to fit snugly within the plate, and the partial exhaustion of the air from the interior of the plate is employed to urge the opposite plate side wall toward the coil structure which forms one side wall of the plate. The points or planes of support are sufficiently numerous to provide a substantial uniformity of plate dimension. The spacing channels abut the coil in good heat transfer relation and, in turn, maintain adequate temperature transfer area within the eutectic to form, in effect, an extension or a fin system for the coil which extends throughout the eutectic body, while being provided with sufficient apertures to permit the circulation or movement of the eutectic within the plate interior.

I claim:

1. In a sheet metal plate for refrigeration and the like, a generally flat sheet metal plate side wall, a second plate side wall spaced therefrom and generally parallel therewith, edge walls connecting said side walls and sealed thereto to form a gas-tight enclosure about the interior of the plate thus formed, said second side wall being constituted by two sheets of metal bonded together, the sheets being generally plane, but being each deformed from such plane to define a sinuous coil located within the periphery of the two sheets, but with the coil having two ends extending to and open at the edge of the plate, inlet and outlet fittings for said coil ends, a spacing assembly loosely positioned in the interior of the plate, and means for maintaining the interior of the plate at a less-than-atmospheric pressure and for thereby causing the excess exterior pressure to urge the plate side walls inwardly against such spacing means and into satisfactory heat transfer relation therewith, the interior of the plate being substantially filled with a eutectic.
2. The structure of claim 1 characterized in that the second plate side wall is formed of aluminum sheets, the inlet and outlet fittings being of copper.
3. In a sheet metal plate for refrigeration and the like, a generally flat plate side wall, a second plate side wall spaced therefrom and generally parallel therewith, edge walls connecting said side walls and sealed thereto to form a gas-tight enclosure about the interior of the plate thus formed, said second side wall being constituted by two sheets of metal bonded together but deformed from each other to define a sinuous coil located within the periphery of the two sheets, inlet and outlet fittings for the coil ends, and a spacing assembly loosely positioned in the interior of the plate, said assembly including a plurality of separate channels positioned to abut the second side wall with the edges of the channels abutting the first side wall, and additional spacing members within the plate formed and positioned to space the channels apart and to maintain the channels in a predetermined position within the plate interior, and means for maintaining a less-than-atmospheric pressure in the interior space of the plate, whereby outside atmospheric pressure is caused to maintain a thrust of the plate side walls toward each other and against the channels, the interior of the plate being substantially filled with a eutectic.
4. The structure of claim 1 characterized in that the spacing means is constituted by a plurality of separate channels, and additional means for spacing the channels

apart and for maintaining them in a predetermined position within the plate interior.

5. The method of making a refrigeration plate which includes forming a bonded coil assembly by bonding two sheets of metal together while spacing them apart along a pattern defining a coil having an inlet and an outlet aperture open at the edge of the coil assembly, forming a sheet metal plate side wall with circumferential edge wall portions terminating in outwardly extending flanges, positioning between the plate side wall and the coil assembly a plurality of loose spacing elements, positioning these loose spacing elements in a predetermined relationship to each other, welding the said flanges to the edges of the bonded coil assembly at a point exterior to

10

the coil pattern, thereafter substantially filling the interior of the plate with an eutectic, and thereafter partially exhausting the interior of the plate, and sealing said interior, while maintaining the interior of the plate at a less-than-atmospheric pressure, and thereby causing the outside atmospheric pressure to urge the bonded coil assembly and the plate side wall toward each other and against the spacing elements.
